RUBBER OVERSHOE

Socha Suender and Emil Gottschalk, New York,
N. Y., assignors to Gem Rubber Corporation,
New York, N. Y.

Application May 5, 1951, Serial No. 15,073

Term of patent 14 years

(Cl. D7—4)

To all whom it may concern:

Be it known that we, Socha Suender, stateless, residing at the city of New York, Borough of Manhattan, county of New York and State of New York, and Emil Gottschalk, a citizen of the United States, residing at the city of New York, Borough of Manhattan, county of New York and State of New York, have invented a new, original and ornamental Design for a Rubber Overshoe, of which the following is a specification, reference being had to the accompanying drawing, forming a part thereof.

In the drawing:

Fig. 1 shows a side view of our new design for a rubber overshoe in the fully turned-down position of the upper edge portion;

Fig. 2 is a side view of the same in a partly turned down position; and

Fig. 3 is a side view of the rubber overshoe in a fully turned up position of the upper edge portion.

We claim:

The ornamental design for a rubber overshoe, substantially as shown and described.

SOCHA SUENDER.
EMIL GOTTSCHALK.
